UNITED STATES PATENT OFFICE.

SAMUEL E. RAHE, OF NEW YORK, N. Y.

MATCH-MAKING MACHINE.

1,184,995.

Specification of Letters Patent. Patented May 30, 1916.

Application filed November 29, 1915. Serial No. 63,924.

To all whom it may concern:

Be it known that I, SAMUEL E. RAHE, a citizen of the United States, and a resident of the city of New York, borough of Brooklyn, county of Kings, and State of New York, have invented a new and useful Improvement in Match-Making Machines, of which the following is a full, clear, and exact description.

10 My invention relates to improvements in match making machines, and more especially to that type of match making machines in which the individual match splints are cut from sheet stock and inserted in a carrier ready for dipping in paraffin and in the firing compositions. In machines of this type the usual practice has been to cut the sticks or splints from the sheet stock which is usually wood veneers, and the sticks are 15 then delivered to the carrier by means of mechanism which is more or less separated from the actual means of sticking the splints into the carrier, and in practice it has been found difficult to properly assemble and 20 stick the splints, as they are very likely to clog or become disarranged in some way in the intervening mechanism between the cutting means and the means which actually does the sticking. The sheet stock, which 25 as stated, is usually wood veneers, is generally the thickness of a match stick, and the width of the sheet usually corresponds to the length of the stick or splint. Where the stock is in the form of wood 30 veneers, another difficulty in cutting has been that it is difficult to split the stock from edge to edge, as the split is likely to follow the grain, and so the splints will not be exactly straight or square in section.

35 The object of my invention is to overcome these difficulties and to produce a machine which will operate with very great rapidity, will cut splints from strips of stock and deliver them as cut directly into the sticking 40 head for insertion in the carrier, so that there is no possibility of the sticks becoming disarranged.

Another object of my invention is to arrange the cutting means so that as one strip 45 of stock is cut into splints, the next strip will be scored so that when said second strip is cut, the knives will follow the scores

already made, and the sticks will be cut straight and smooth without splintering.

Another object of my invention is to provide means for cutting the sticks and arranging them directly in the sticking head in such a way that a plurality of rows of splints separated the correct distance can be simultaneously and firmly inserted in the carrier.

Another object of my invention is to construct and arrange the machine so that a whole series of stock strips can be piled one on the other in a hopper and automatically fed by gravity to the cutting and sticking means.

In general my invention is intended to provide a match making machine of great capacity which uses sheet stock and cuts the same to advantage into splints, delivers these directly as cut into the sticking head, and inserts them in the carrier ready for dipping.

Reference is to be had to the accompanying drawings forming a part of this specification, in which similar reference characters indicate corresponding parts in all the views.

Figure 1 is a broken plan view of the mechanism embodying my invention. Fig. 2 is a broken front elevation of the same. Fig. 3 is a cross section on the line 3—3 of Fig. 1, with the sticking head in the position which it assumes just as the splints have been inserted in the carrier and the head started on its return movement. Fig. 4 is a view similar to Fig. 3 but with the sticking head retracted or at the opposite end of its stroke from that shown in Fig. 3. Fig. 5 is an enlarged broken perspective view in section showing the cutting mechanism in the act of cutting the splints and scoring one of the stock sheets. Fig. 6 is a detail plan view of a portion of the sticking head. Fig. 7 is a cross section on the line 7—7 of Fig. 6, looking in the direction of the arrows. Fig. 8 is a broken rear elevation of the cleaning comb for cleaning the splint channels or grooves in the sticking head. Fig. 9 is a detail of a pair of splint cutting knives, and Fig. 10 is a broken detail perspective view of one of the knife blocks for holding the knives in place on the sticking head.

The machine is provided with a hopper 10 in which a series of sheets of stock 11 can be piled one on the other, these sheets being of a width corresponding to the length of the match splints, of a thickness corresponding to the thickness of the splints, and of a length to fit the hopper 10. They lie flatwise one on the other as shown clearly in Figs. 3 and 4. The hopper 10 is arranged 5 opposite the carrier 12 which is usually in the form of a series of plates linked together and provided with suitable driving means, and having holes 13 to receive the match splints 11^a, so that when the splints are 10 driven into the holes they will be held in parallel relation spaced apart so that when dipped the heads will remain separated. As shown the carrier plates 12 have the holes 13 in staggered relation, and this machine is 15 provided with means for filling two rows of holes at a time, but so far as my present invention is concerned the carrier can be of any approved kind which will receive and hold the match splints. In practice such a carrier is made long enough to carry the splints forward to the devices for dipping them, and then drying them, after which they are ejected. This invention relates, however, entirely 20 to the means for cutting the sticks and 25 inserting them in a suitable carrier.

Directly beneath the hopper 10 is a reciprocating sticking head having a slide 14 which moves back and forth perpendicular to the carrier, and is provided with a rod 15 for moving it. Any suitable mechanism can be used for reciprocating the sticking head. The head is preferably provided with a housing 16 which covers it when in its retracted position, as in Fig. 4. On the slide 30 14, at its inner end, is a block 17 and this is fast to the slide 14, and as a matter of convenience there are several of these blocks arranged side by side, although so far as the invention is concerned the block might be 35 made in a single piece. The block is provided with grooves or channels 18 and 19, the grooves 18 lying at a lower level than the grooves 19, and the match sticks 11^a when 40 they are cut are dropped into these grooves or channels and when the sticking head moves forward to the position shown in Fig. 3, the sticks contained in said grooves are forced into the holes 13 of the carrier plates 12. Immediately 45 behind the block 17 is a plate 20, also fast to the slide 14, and this is made a little thicker than that part of the block 17 which forms the bottom of the grooves or channels 18, as shown in Figs. 3 and 4, so that the inner end of the plate 20 50 will serve as an abutment or shoulder to engage the outer ends of the splints 11^a and force them into the carrier plates. The grooves 19 which are at a higher level than the grooves 18, have a shoulder at their 55 outer ends formed by the ribs 21 which rise

from the slide 14. So far as the invention is concerned it does not matter whether the parts 14, 17 and 20 are a single piece or separate pieces as shown, but it is more convenient to make them in separate pieces.

At the inner ends of the plate 20 are knives 22 which for convenience are made U shaped as shown clearly in Fig. 9, having cutting edges 22^a at their upper extremities, and essentially vertical cutting edges 22^b at 70 their rear or outer parts. In practice these knives, and especially the cutting edges, are made very thin, but in the drawings said parts are exaggerated and appear somewhat thick in order that they may be clearly 75 shown. The knives are preferably held in place by means of the knife blocks 25 which lie between the ribs 21 on the plate 20, and have reduced ends 24 which fit closely between the side members of each knife and 80 lie upon the bottom part thereof as shown in Figs. 5, 9 and 10.

It will thus be seen that the part of the sticking head comprising the plate 20, the ribs 21 and the knife blocks 25, are flat on 90 top and at a little lower level than the tops of the knives 22, and that these knives are above the top of the plate or block 17. It will also be observed by reference to Fig. 7 that the vertical members of the knives 22 95 align with the partition walls of the grooves or channels 18 and 19 (see Fig. 7), and that the knives are slightly thicker than said partition walls so that when the splints 11^a are cut, they are in position to fall horizontally directly into the channels or grooves of the sticking head, and that a little clearance is provided so that they will fall readily to place. The outer wall of the hopper 10 is provided with recesses 10^a through 100 which the upper parts of the knives 22 can pass as the knives reciprocate beneath the hopper.

To provide for cleaning the grooves or channels 18 and 19 so that there will be no 110 accumulation of dust, slivers, or the like therein, I use a cleaning comb 26 which can be reciprocated by any suitable means, and which when the sticking head returns on its movement away from the carrier plates 12, 115 drops and permits the teeth 27 and 28 to enter the channels or grooves 18 and 19 of the sticking head, and thus thoroughly clean the grooves. As the sticking head reaches the outer limit of its stroke, the comb 26 is 120 raised so as not to interfere with the insertion of the match sticks in the carrier.

When the sticking head is moved forward toward the carrier plates 12, it will slide beneath the pile of sheets 11, and the lower sheet will drop down and lie flatwise on the outer part of the sticking head opposite the edges of the knives, and on its return movement the knives 22 will cut the lower sheet 11 into splints 11^a, this being done by the 130

- cutting edges 22^b of the knives 22, and the severed splints will fall directly into their receiving channels 18 and 19 of the sticking head. While this cutting is in progress, the 5 upper edges 22^a of the knives will cut into the second sheet 11 of stock as shown clearly in Fig. 5, thus scoring the sheet. By reference to Fig. 4 it will be seen that the knives 22 which have scored the sheet above the 10 one just cut, will have their upper edges in absolute registry with the scoring slits which they have just made, and just on the point of entering the slits on the back stroke of the knives and sticking head so that the 15 cutting edges and the slotted portions of the stock are sure to register. It is obvious, however, that both front and rear edges of the knives 22 can be thinned if desired without affecting the principle of the invention. 20 When this second sheet is cut in the manner already described, the knives 22 will easily follow the score marks in the sheet 11, and cut it accurately without any danger of slivering. It will thus be seen that after 25 the first sheet is cut, each succeeding sheet will be scored as described to provide for cutting very accurate splints. It will be understood that after the two rows of splints are stuck in the carrier plates 12, the said 30 plates will be stepped forward a distance to bring the next two rows of holes into registry with the next two rows of splints. I have not shown this mechanism, as it is common to all match machines of this character. 35

I have shown and described a construction which is simple and practical for carrying my invention into effect, but it will be understood that the details of construction 40 can be departed from, and different forms of cutters used without in the least affecting the principle of my invention, the important thing being to have the stock arranged as shown, and to have the knives arranged 45 to cut the stock in the manner specified and deliver the severed splints directly into the grooves of the sticking head without any intervening mechanism.

I claim:

- 50 1. In a match machine for cutting sheet stock, the sticking head having match receiving grooves or channels near one end thereof, and stick slitting knives adjacent to the ends of the grooves or channels, said 55 knives being in substantial alinement with the walls of the grooves and projecting above the said walls and having exposed edges parallel with the channels and opposed to the movement of the sheet toward 60 the plane of the channels so as to cut through the stock.

2. In a match machine for cutting sheet stock, the sticking head having match receiving grooves or channels therein, said 65 grooves being open at the top and at one

end, and knives arranged near the end walls of the grooves and projecting above and in alinement with said walls and having exposed edges parallel with the channels and opposed to the movement of the sheet toward the plane of the channels so as to cut through the stock, the knives having said edges and their end edges sharpened. 70

3. In a match machine for cutting sheet stock, the sticking head having match receiving grooves or channels at its inner end and upper part, substantially U shaped knives arranged behind the grooves with their side members substantially alining with the walls of the grooves and with their longitudinally spaced edges projecting above the walls of the grooves so as to cut through the stock, said knives having cutting portions at their upper and outer edges. 75

4. In a match machine, the sticking head 85 having match receiving grooves or channels at its inner end and upper part, generally U shaped knives arranged behind the grooves and with the side members of the knives projecting above the walls of the grooves, 90 and knife blocks secured to the sticking head and having their ends entering between the side members of the aforesaid knives.

5. A match machine for cutting sheet 95 stock comprising a reciprocating sticking head having split receiving grooves at its inner end and upper part, the grooves being open at the top and at the inner end, a splint carrier opposite the inner end of the sticking head, knives arranged behind the walls of the grooves and projecting above and in alinement with the said walls having exposed edges parallel with the channels and opposed to the movement of the sheet toward the plane of the channels so as to cut through the stock, and means for supporting a pile of sheet stock so that the lower sheet will lie flatwise on the top walls of the aforesaid grooves, whereby the splints severed by the knives will drop directly into the grooves. 100 105

6. In a match machine the combination with the reciprocating sticking head having splint receiving grooves at its inner end and upper part, said grooves being open at the inner end and at the top, of means for supporting a pile of sheet stock directly above the aforesaid grooves, and knives moving with the sticking head and in substantial alinement with the walls of the aforesaid grooves, said knives projecting above the walls and having cutting edges at their upper and inner parts, whereby said knives cut through the lower sheet of stock and 110 score the next sheet above. 115 120

7. A match making machine for cutting beet stock comprising a hopper arranged to contain a pile of sheet stock, a splint carrier, a sticking head reciprocating below the hop- 125 130

per and perpendicular to the splint carrier, said sticking head having splint receiving grooves or channels on its upper side and inner end, the walls of the channels lying in contact with the lower sheet of stock, and knives arranged behind the walls of the grooves and projecting above the same and having exposed edges parallel with the

channels and opposed to the movement of the sheet toward the plane of the channels 10 to engage and cut through the lower sheet of stock.

SAMUEL E. RAHE.
